UNITED STATES PATENT OFFICE.

JOSEF HOFMANN, OF BAUMAROCHE, SWITZERLAND.

SHOCK-ABSORBER MECHANISM.

1,297,849.

Specification of Letters Patent. Patented Mar. 18, 1919.

Application filed August 31, 1917. Serial No. 189,135.

To all whom it may concern:

Be it known that I, JOSEF HOFMANN, a citizen of Switzerland, residing at Baumaroche, Switzerland, have invented certain new and useful Improvements in Shock-Absorber Mechanisms; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to means applicable to vehicles to improve the suspension of the body thereof, and is used in conjunction with the main vehicle springs or body springs.

The object of the invention is to decrease as far as possible the motion of the body with respect to the running gear, and to avoid the pitching of the body, and also provide means for compensating for load.

The invention, therefore, consists in the combination and arrangement of parts of the mechanism included between the body or frame of the vehicle and its main springs.

Referring to the drawings, in which like parts are similarly designated—

Figure 1 is a side elevation illustrating mechanism embodying my invention.

Fig. 2 is a like view, certain parts removed to obtain a different effect.

Fig. 3 is a view similar to Fig. 2, with the addition of front shock absorbing means.

Fig. 4 is a view similar to Fig. 1, but employing other parts than those of Figs. 2 and 3.

In Fig. 1, the frame 1 is provided with a member or rear extension 2. The rear axle 3 carries a well-known type of body spring 4, the forward end of which is connected to the frame by a shackle 5.

The front axle 6 carries a front spring 7 having its rear end connected to a bracket 8 secured to the frame 1.

Between the rear end of the rear spring 4 and the end of the frame extension 2 I secure a shock absorber consisting of a plurality of pivotally connected levers as follows:

Secured to the end of the body spring 4

is a lever 9—10 pivotally connected to the spring end at 11 between the portions 9 and 10 and the forward end of the arm 9 is held to the spring 4 by means of a clamp 12. The arm 10 of the lever is downwardly and outwardly inclined, and this inclination can be adjusted by raising or lowering the arm 9, the degree of adjustability being controlled by shims, not shown, slipped between the arm 9 and the spring 4 and held tight by clamp 12. Any other means may be used to effect the adjustment, as may seem desirable.

Pivoted at 10^a in the end of the arm 10 hanging over the end of spring 4 is a lever 13, having between its ends an offset 14 to which is pivotally connected at 14^a one end 70 of a link 15 curved substantially as shown. The other end of link 15 is pivoted to the end of the frame extension 2 at 2^a.

The end of the lever 13 has a cylindrical portion on which is secured a split sleeve 16, said sleeve being adjustable along the cylindrical portion 13^a and forming an adjustable leverage connection for a spring retracted belt 17. One end of the belt 17 is connected to the sleeve 16 and to the other end is connected a spring 18 that is either directly or indirectly connected to a wire rope 19 or the equivalent, for increasing or diminishing the action of the spring. This rope 19 passes over a roller 20 to a winding spindle 21 provided with a squared end for the reception of a wrench. The spindle is mounted in a bracket 22 on which is pivoted a pawl 23 engaging a ratchet wheel 24 secured to the spindle 21 and arranged to prevent the unwinding of the rope from the spindle.

In said Fig. 1 the spring 18 is connected indirectly to the rope 19. That is to say, it is connected to the lower end of a bell-crank lever 25—26, pivotally mounted at 27 in a bracket 28 secured to the rear spring 24. The upper arm 26 of this bell-crank lever has pivoted thereto one end of a link 29 whose other end is pivoted to a bracket 30 on the frame 1. Interposed between the arm 25 and rope 19 is a second spring 31.

Included between the downwardly bent front of the frame and the front spring 7 is a shock absorber comprising a curved link 32 the upper end of which is pivoted to

the front of the frame, and the lower end is pivoted to a short arm 33 of a double bell-crank lever 34. The upper end of lever 34 is pivoted to the end of body spring 7, and to the lower end is connected one end of a spring 35 the other end of which is spring-connected to a bracket 20^a.

I provide at the rear shock absorber a removable shackle 36 which is inserted or removed by the vehicle owner between the end of extension 2 and the center 11 at the end of the spring 4.

The mechanism thus described is duplicated at the other side of the vehicle.

15 The insertion of the shackle 36 eliminates the action of the rear shock absorber, as it forms a direct connection between the end of frame extension 2 and the rear end of main spring 4.

20 In this instance the bell-crank lever 25—26 and link 29 is effective to prevent pitching of the vehicle in connection with the rope 19 passing to the take-up spindle 21 over roller 20. Assume that the front of the frame 25 rises from the front axle. The rope 19 secured to the frame 1 passes under the front axle and is drawn over roller 20. The coil spring 31 is tightened creating an extra pull on lever arm 25 causing lever arm 26 to 30 swing to the left increasing the angle between arm 26 and link 29, thereby causing the rear of the frame 1 to move up also, so that the body will rise in a parallel plane, or nearly so.

35 On the other hand, if the front spring 7 approaches the frame, the rope 19 is slackened, allowing arm 26 of bell-crank lever 25—26 to move to the right and allow the frame 1 to approach spring 4, thus maintaining a parallel downward movement of the frame 1 instead of a downward movement at one or the other end of the frame causing the unpleasant pitching.

When additional passengers or luggage 45 are added, say at the rear, spindle 24 is wound up to tighten spring 31 and open the angle between arm 27 and link 29 and thus supplement the main spring 4 at the same time the front end of the frame is 50 drawn down to a substantially horizontal line.

The front shock absorber operates to ease the transmission to the frame of heavy jolts received by the front wheels. Link 32 acts 55 on the short arm 33 to swing lever 34 to the right when the front axle 6 approaches the frame 1, thus extending coil spring 35. This spring therefore acts to retard the movement of the front axle toward the frame.

60 When the front axle tends to rebound from the frame, lever 34 swings to the left, thus releasing the coil spring 35, allowing the load on the frame to follow the front axle downward.

Upon removing the shackle 36 at the rear 65 shock absorber this shock absorber becomes active and acts in connection with the rope 19, as will presently be explained.

The adjustable spring-sleeve 16 is adjusted along the cylindrical extension 13^a so 70 that the dead load will be properly adjusted with respect to the pull of spring 18. The pivot between arm 14 and link 15 is properly to the right of a line through the pivot points 2^a and 11. 75

When the rear axle 3 rises with respect to the frame 1, the end 11 of the main spring moves toward the pivot point 2^a thus moving the arm 14 around pivot point 11 as a center until the pivot points 11, 10^a and 14^a are 80 in alignment. Any further movement would tend to raise the pivot 2^a directly, and not through the medium of the main spring. Before reaching this point in the movement of the levers, the pivot point 14^a touches the 85 belt 17, thereby causing the belt 17 to be drawn about an arc with 10^a—14^a as a radius and extending the spring at a more rapid rate than if extended by the radius 10^a—16. The reason for this is that when the points 90 11, 10^a and 14^a are alined the point 16 is in the last part of its quadrant of movement and the cosine of the angle increases at a lower rate as it approaches a horizontal, while by transferring the point of action to 95 14^a which is more nearly vertical, the cosine of the angle changes at a faster rate.

The coil spring 18 tends to rapidly return the parts of the shock absorber to normal position, and this action is assisted by a pull 100 on the rope throwing the front axle and front part of the frame together. This action of increasing the resistance at the end of the movement of the respective parts is the aim of all spring makers, as it is preferable to arrest the motion gradually, rather than by allowing the frame to strike a bumper or the axle. 105

When the axle moves downward from the frame 1 pivot point 14^a moves upward, 110 thus causing point 16 to swing to the right, releasing the coil spring 18 and at the same time releasing the rope 19, so that the front axle and body will be free to separate under the action of the main spring 7 and coil 115 35.

The gravity of the vehicle body and the reduced resistance of the coil springs bring the levers to their normal position.

In Fig. 2 I have illustrated the use of the 120 rear shock absorber combined with the rope 19 and its winding mechanism thereby combining the rear shock absorber with anti-pitching means, the front shock absorber being omitted.

In Fig. 3 I have illustrated a mechanism the same as shown in Fig. 2, but with the addition of the front shock absorber, and in

Fig. 4 I have shown only the construction that mitigates the pitching action. In this figure the shackle 36^a has an extension 36^b depending below the pivotal connection at 5:11 to permit the coil spring 18 to be interposed between it and lever 25, as without spring 18 the spring 31 would tend to stiffen the suspension unnecessarily. The spring 18 offsets the stiffening action of spring 31 10 without interfering with this latter spring in counteracting the pitching. However, should it be desired to obtain a stiffer suspension by omitting spring 18 this may be done, at the option of the user.

15 Any of the structures illustrated in Figs. 2, 3 and 4, embodying less than the whole number of mechanisms illustrated in Fig. 1, may be used, according to the particular conditions to be met, and it will be a simple 20 matter to change an automobile equipped with the structure shown in Fig. 1 to any of the other forms.

For example, if the shackle 36 eliminates the action of the rear shock absorber, a like 25 shackle inserted between the front spring and the frame will also eliminate the action of the front shock absorber, if the vehicle suspension is too soft.

In addition to the above, by releasing the 30 rope 19 to such an extent that there will be no tension on the springs 18 or 31 the action of the anti-pitching device is eliminated, and the vehicle will then be subjected only to the action of the main springs.

35 I claim—

1. The combination with a vehicle frame and a main spring; of a lever having an extending arm between its ends, said lever pivotally connected at one end to the end of 40 the main spring, a coil spring under tension connected to and having influence only on the other end of said lever, and a link pivoted at one end to a frame member and at its other end to said arm.

45 2. The combination with a vehicle frame and a main spring; of a lever having three points of connection, one of said points being connected to the end of said main spring, a coil spring under tension being 50 connected to another point of said lever, and a link pivotally connected at one end to a frame member and pivotally connected at its other end to said third point, the third point of said lever being out of alignment 55 with the other two points and arranged to swing across the line of pull of said spring and produce an additional tension thereon.

3. The combination with a vehicle frame and a front and rear main spring and the 60 axles thereof; of a shock absorber connected between a frame member and the rear end of one of said springs, and a flexible connecting element between said shock absorber and a frame member and passing under

the axle at the other spring, and a coil 65 spring interposed in said flexible connecting element.

4. The combination with a vehicle frame and a front and rear main spring and the axles thereof; of a shock absorber connected 70 between a frame member and the rear end of one of said springs, and a flexible connecting element between said shock absorber and a frame member and passing under the axle at the other spring, and a coil spring 75 interposed in said flexible connecting element, and means to shorten and lengthen said flexible connection and thereby vary the tension of said coil spring.

5. In combination with a vehicle frame 80 and a main spring; of a two-armed lever rigidly connected to the end of said main spring and having a downwardly and outwardly inclined arm, a lever pivotally connected at one end to the aforesaid lever arm, a coil spring under tension connected to the other end of the latter lever, and a link pivoted at one end to a frame member and at its other end intermediate the ends of 85 the second lever.

6. In combination with a vehicle frame and a main spring; a two-armed lever rigidly and adjustably connected to the end of said main spring and having a downwardly and outwardly inclined arm, a lever 90 pivotally connected at one end to the aforesaid lever arm, a coil spring under tension connected to the other end of the latter lever, and a link pivoted at one end to a frame member and at its other end intermediate 95 the ends of the second lever.

7. The combination with a vehicle frame, a main spring and front axle; of a lever having three points of connection, one of said points being pivotally connected to the end of said main spring, one end of a coil spring connected to the other end of said lever, a link pivotally connected to a frame member and pivotally connected intermediate the ends of said lever, a bell crank 105 lever pivotally mounted between the ends of said main spring and having an arm connected to said spring, a link pivotally connected to the other arm of said bell crank lever and to said frame, a flexible connecting element between said bell crank lever passing under the front axle and connected to the frame, and a coil spring interposed in 110 said connecting element.

8. The combination with a vehicle frame, 120 two springs and their supporting axle; of a bell-crank lever pivotally mounted between the ends of one of said springs, a link pivotally connecting the frame and one end of said bell-crank lever, a flexible, adjustable 125 connecting element between the other end of said bell-crank lever and a frame member, passing under the axle for the other spring

and connected to the frame, and a coil spring interposed in the connecting element.

9. The combination with a vehicle frame and a main spring; of a lever having three connecting points, one of said points pivotally connected to the main spring, a link pivotally connecting the intermediate point of said lever to said frame, a coil spring

connected to the third point of said lever and means to adjust the point of connection 10 of said coil spring along said lever for balancing the dead load.

In testimony that I claim the foregoing as my invention, I have signed my name thereto.

JOSEF HOFMANN.
